DESIGN FOR A BUILDING BLOCK

Alfred H. Stamm and Harry S. Barton, Peoria, Ill.

Application September 3, 1938, Serial No. 79,735

Term of patent 3½ years

To all whom it may concern:

Be it known that we, Alfred H. Stamm and Harry S. Barton, both citizens of the United States, residing at Peoria, in the county of Peoria and State of Illinois, have invented a new, original, and ornamental Design for a Building Block, of which the following is a specification, reference being had to the accompanying drawing forming part thereof.

Figure 1 is a perspective view of a building block showing our new design, and;

Figure 2 is an end elevation of the same.

We claim:

The ornamental design for a building block, as shown.

ALFRED H. STAMM.
HARRY S. BARTON.
